Patented Aug. 11, 1914.

FIG. 1.

UNITED STATES PATENT OFFICE.

MICHAEL BANDRINGA, OF CHICAGO, ILLINOIS.

SQUEEGEE.

1,107,131.

Specification of Letters Patent. Patented Aug. 11, 1914.

Application filed April 13, 1914. Serial No. 831,658.

To all whom it may concern:

Be it known that I, MICHAEL BANDRINGA, a citizen of the United States, residing at Chicago, in the county of Cook and State of Illinois, have invented certain new and useful Improvements in Squeegees; and I do hereby declare the following to be a full, clear, and exact description of the invention, such as will enable others skilled in the art 10 to which it appertains to make and use the same.

This invention relates to window cleaners, and more especially to those of that type known as squeegees, and the object of 15 the same is to produce a device of this kind whose working edge is made of several plies or laminations, so that when one becomes worn or hardened in usage, it may be torn off or cut off to expose the next lamination.

20 A further object is to produce a device of this character where the laminations or strips grow successively narrower or are stepped, so that the tool can be inverted at times when it is desired to give an extremely 25 fine finish to the surface being treated.

With this and other objects in view the invention comprises details of construction as set forth in the following specification and shown in the drawings herein—

30 Figure 1 is a perspective view of this window cleaner ready for use. Fig. 2 is an end elevation of the head of the implement inverted, showing how it may be employed so that the forward edges of all its strips 35 contact with the glass. Fig. 3 is a bottom plan view of part of the head of the tool, showing the lowermost or widest strip as being removed.

As usual with the devices of this kind 40 an ordinary long wooden handle, H, carries a ferrule, F, at its upper end, the same being secured in a suitable manner as by screws S to a head M which may well be a piece of wooden molding of the desired 45 length.

The active edge of the squeegee is as usual made of rubber, but in the present invention it is composed of a series of rubber laminations or strips, 1, 2, 3, 4, 5, overlying 50 each other as illustrated, the uppermost strip 1 being the narrowest and the others successively wider as shown; and the rear edges of all strips standing flush at 6 in the bot-

tom of a rabbet formed along the under side of the head M. Any suitable means may be 55 employed for holding said rear edges in place, but as shown herein I use a metal strip 7 which underlies the rear edge of the widest rubber strip 5 and pass screws or nails 8 upward through the metal strip and 60 all the rubber strips into the head M.

While I have stated that the strips constituting the active edge of the implement are of rubber, I do not wish to be limited strictly thereto, as rubber composition or other material might be employed.

It is essential, however, to the gist of the present invention that the laminations or strips grow successively wider so that they will present a working edge which is 70 stepped, as perhaps best seen in Figs. 1 and 2. This makes the lowermost and widest strip 5 quite flexible, but it is prevented from flexing upward unduly by the presence 75 of the other strips above it.

In use, the operator who is washing a window commonly wets it and sponges it with a suitable tool carried by a long handle so that he can reach the window from the ground. The squeegee is then brought 80 into use, and the front edge of the lowermost strip pressed against the pane near the top of the latter and wiped slowly downward over the window-pane as well understood. This is repeated clear across the 85 pane, with the result that the moisture is wiped off and the surface is left clean and dry. It may be desirable in some cases, with some kinds of glass or under certain 90 conditions of the weather, to invert or reverse the head M of the squeegee and wipe the working edges of all the strips downward over the pane as seen in Fig. 2; and this will give an extremely fine finish to the 95 job.

In time the corner of the widest strip 5 will become worn or possibly broken or torn by long use of the tool, and the operator may then tear or cut off this strip 5 as seen in Fig. 3. He may either run a knife along the edge of the metallic strip 7 and cut the rubber strip 5 partly through and then tear it the rest of the way and remove it entirely; or if this rubber strip be thin enough he can simply tear it off if it be started at 105 one end. Its removal leaves the second strip

4 projecting beyond the working edges of the strips above it and the implement may yet be used successfully for some time, after which this strip also may be removed when 5 it becomes worn or damaged, and then the next strip 3, and so on. It is quite possible that a strip or strips could be replaced by others as by removing the nails or screws 8 and metal strip 7 and substituting new rubber strips for those which are damaged.

10 The gist of the invention, however, lies in making the working edge or rubber portion of the squeegee in laminations or strips whose rear edges are secured to the head 15 and whose front edges are disconnected from and disposed in stepped relation to each other, the uppermost strip being the narrowest and the lowermost the widest.

Modifications in and amplifications of 20 this general idea may be resorted to without departing from the principle of the in-

vention. The proportions of parts are obviously immaterial.

What is claimed as new is:

A squeegee comprising a handle, a head 25 having a rabbet, an active edge composed of strips of flexible material of different widths, their rear edges standing flush with in the said rabbet and their front edges disposed in stepped relation to each other, the 30 lowermost strip being the widest, a metallic strip underlying these flexible strips near their rear edges, and fastening devices passing up through the metallic strip and the 35 flexible strips into said head.

In testimony whereof I affix my signature in presence of two witnesses.

MICHAEL BANDRINGA.
